ATTORNEY

UNITED STATES PATENT OFFICE.

ISIDORE PETER SMITH, OF CHICAGO, ILLINOIS.

DESIGN FOR AN AUTOMOBILE TIRE.

61,333.

Specification for Design.

Patented Aug. 1, 1922.

Application filed February 16, 1920. Serial No. 359,191. Term of patent 14 years.

To all whom it may concern:

Be it known that I, ISIDORE PETER SMITH, a citizen of the United States, residing at Chicago, Illinois, in the county of Cook and State of Illinois, have invented a new, original, and ornamental Design for Automobile Tires, of which the following is a specification, reference being had to the accompanying drawing, forming part thereof.

The figure is a plan view of an automobile tire, showing my new design.

I claim:

The ornamental design for an automobile tire, as shown.

ISIDORE PETER SMITH.
